UNITED STATES PATENT OFFICE

HOWARD T. HALLOWELL AND FRANK BENNETT, OF JENKINTOWN, PENNSYLVANIA,
ASSIGNORS TO STANDARD PRESSED STEEL CO., OF JENKINTOWN, PENNSYLVANIA, A
CORPORATION OF PENNSYLVANIA

PLATFORM

Application filed November 18, 1929. Serial No. 408,035.

This invention relates to certain improvements in platforms which are supported on comparatively short legs and of such height that a truck can be inserted between the legs and raised to elevate the platform from the floor. Platforms of this type are used in factories and warehouses for supporting goods.

The object of our invention is to securely attach the legs to the body of the platform.

In the accompanying drawings:

Fig. 1 is a side view of our improved platform;

Fig. 2 is an end view;

Fig. 3 is an enlarged sectional view showing the legs secured to the Z-beam of the platform;

Fig. 4 is a sectional view of another method of securing the legs to the platform; and

Figs. 5 to 9 are views illustrating modifications of the invention.

The body 1 of the platform consists, in the present instance, of a metallic plate flanged at each side and end as at 2-2 and 3-3 respectively. The lower edges of the flanges are turned inwards as at 4 to form what may be termed a channel edge. This channel edge at each end of the platform may be reinforced by an angle bar 5 as shown in

Figs. 1 and 3, or a flat bar 5a as shown in Fig. 5; and in some instances the inturned edge 4 of the flange may be turned over upon itself as at 4a in Fig. 6 to strengthen the ends of the platform to resist end thrusts of trucks.

The body of the platform is reinforced by transverse beams 6 and 7. The beams 6 are, in the present instance, Z-bars, while the central beam is a flanged channel beam. The beams are secured at their ends to the side flanges and to the body of the platform by welding.

It will be noted in Figs. 1 and 3, that the webs 10 of the Z-bars 6 are inclined and the side members 8-8 of the legs 9 are on the same incline as the webs of the Z-bars, so when the parts are assembled, the side members 8-8 lie flat against the webs of the Z-bars. The members 8-8 are welded to the webs 10 of said Z-bars. This construction is very strong, and as the legs are comparative-

ly wide they will resist any shocks to which the platform is subjected.

In Fig. 3 both side members of the leg 9 are secured to the webs 10 of the Z-bars 6, while in Fig. 4 only one side member is secured to the web of a Z-bar, the other member being secured to the channel member 2a which forms the end flange of the platform. The plate 1a in this instance is flanged only at the sides.

Fig. 5 shows a side member 8a of a leg welded at its upper end to the underside of the platform and also welded to the inturned edge 4b of the flange 2b.

In Fig. 7 the web 10a of the Z-bar 6a is vertical and the members 8b of the legs 9b are bent at their upper ends so that they will rest against the webs 10a to which they are secured, preferably by welding.

In Fig. 8 the flanges of the bars 6b are turned in the same direction while the webs 10b are inclined.

In Fig. 9 channel bars 6c are used in place of the Z-bars. The members 8c are secured to one web 10c of each channel bar.

In each case the inclined members of the legs are secured to the webs of the shaped bars or beams which support the body of the platform.

We claim:

1. The combination in a platform, of a plate; shaped bars extending across the body of the platform and secured to the plate, said bars having webs; and longitudinally arranged legs having side members fitting against the webs and secured to said bars.

2. The combination in a platform, of a body portion consisting of a plate flanged at the side, said flanges being inturned; Z-bars extending across the platform under the plate and extending into the channels formed by the inturned flanges, said Z-bars being secured to the plate by welding; and U-shaped legs having inclined side members, the incline of the side members being on the same angle as the webs of the Z-bars, the legs being secured to the bars by welding.

3. The combination in a platform, of a plate having flanges at the sides and ends; Z-bars extending across the platform under

the plate at points between the ends thereof and secured to the side flanges; legs secured to the webs of the Z-bars; and reinforcing plates located back of the end flanges of the platform and extending parallel therewith.

4. The combination in a platform, of a plate; shaped bars extending from one side of the body of the platform to the other side thereof, the bars having inclined webs; and U-shaped legs supporting the platform, the flat surfaces of the upper ends of the legs being parallel with the inclined webs of the bars and secured to said bars.

5. The combination in a platform, of a plate; Z-bars extending under the plate from one side of the platform to the other side thereof and secured to the plate; and longitudinally arranged legs at each side of the platform, the side members of said legs being inclined on the same angle of the Z-bars, the flat surfaces of the legs being secured to the webs of the Z-bars.

6. The combination in a platform, of a plate having flanges at the sides and ends; Z-bars intermediate the ends of the plate and extending from one side of the plate to the opposite side thereof and secured to the underside of said plate and to the side flanges of the plate; and longitudinally arranged legs at each side of the platform, the flanged surfaces of the legs being secured to the webs of the Z-bars.
